Des. 221,572
Patented Aug. 24, 1971

221,572

COMBINE HARVESTER

Robert Ashton, Islington, Ontario, and Walter Hirsch,
Don Mills, Ontario, Canada, assignors to Massey-
Ferguson Industries Limited, Toronto, Ontario, Canada

Filed June 15, 1970, Ser. No. 23,501

Term of patent 14 years

Int. Cl. D12—09; D15—03
U.S. Cl. D40—1

Fig. 1

Fig. 2

Fig. 3

Fig. 4

FIG. 1 is a left front perspective view of a self-propelled combine harvester embodying our new design;

FIG. 2 is a left side view of the combine harvester shown in FIG. 1;

FIG. 3 is a left rear perspective view of the combine harvester shown in FIG. 1;

FIG. 4 is a right front perspective view of the combine harvester shown in FIG. 1.

We claim:

The ornamental design for a combine harvester, substantially as shown and described.
